FIG.1

FIG.2

INVENTOR:
H. A. NICHOLSON

BY: *Frank J. Deem*

ATTORNEY

UNITED STATES PATENT OFFICE.

HENRY ANGUS NICHOLSON, OF AUCKLAND, NEW ZEALAND, ASSIGNOR TO ERNEST A. CRAIG, OF AUCKLAND, NEW ZEALAND.

STEAM-GENERATOR.

1,366,207.

Specification of Letters Patent. Patented Jan. 18, 1921.

Application filed January 7, 1918. Serial No. 210,690.

To all whom it may concern:

Be it known that I, HENRY ANGUS NICHOLSON, subject of the King of Great Britain, residing at 95 Queen street, Auckland, in 5 the Dominion of New Zealand, have invented new and useful Improvements in Steam-Generators; and I do hereby declare the following to be a full, clear, and exact description of the same.

10 This invention has been devised in order to provide improvements in the construction and operation of steam generators designed for use either as ships' boilers or as stationary land boilers and to produce a generator that will be economical in use and in which the steam may be generated at a rapid rate. The invention may also with slight alteration, be used as a water heater.

One of the main features of the invention 20 relates to the employment of producer gas mixed with hot air as a heating agency of the generator, and the submission of the water in a number of tubes to the action of heat, so that the water is converted 25 through a number of stages (including a superheating stage) into steam for subsequent power uses.

The invention comprises a novel construction embodying a gas producer and an arrangement 30 of water tubes around such producer that are contained within a combustion chamber or chambers into the lower end of which the gas from the producer is introduced in a number of jets and mingled 35 with jets of hot air and the whole combusted to act upon the water tubes.

The invention may be carried out in a number of ways by which the general principle of working may be effected. The accompanying 40 drawings illustrate a suitable structure of steam generator embodying the general features concerned.

In such drawings:

Figure 1 is a vertical section of the complete 45 generator.

Fig. 2 is a sectional plan thereof taken on the line 2-2 of Fig. 1.

The form of generator shown is square 50 in its cross-sectional shape but it will be readily understood that it may be made circular, elliptical, oblong or any other desired shape to suit the special circumstances of the case according to the economy of space required in assembling a number of 55 such generators together.

The generator is formed by the gas producer A of any ordinary type having the grate A' at its bottom and a closed ash pit B, and also the usual charging means C at its upper end. If desired however the 60 charging may be performed by mechanical means so as to provide for the regular automatic maintenance of the fuel necessary for the production of the gas. In like manner also, the ash may be removed from the 65 ashpit B by mechanical means, if so desired. Air is introduced into the top of the generator through the pipe D leading from a source of air compression and the inlets d arranged around the upper end of the generator. The steam required in the production of the gas is also introduced into the upper end of the producer through the steam pipe E which may, as shown, enter the air admission pipe D, or be separately 70 introduced.

The gas produced passes from the bottom of the producer through a number of ducts F leading from it at a point above the grate A' and at intervals around it. These ducts 80 are arranged to lead upward on the outside of the producer, as shown in Fig. 1.

The producer described and shown is of the downdraft type supplied with air under pressure from a suitable source such 85 as a fan or blower, but it will be understood that a producer of the updraft type supplied either with air under pressure or induced, may be adapted for the purposes of this invention.

The wall of the producer is surrounded by a jacket G inclosing a water space G', and outside this jacket, is the outer shell H of the generator, which is so disposed as to provide a clear space H' all around and 95 which space forms the combustion chamber of the generator. The gas ducts F lead into the bottom of the combustion chamber, and air to insure and support the combustion of the gas is also admitted to the bottom of this chamber through air apertures J arranged at intervals around a supporting plate J'. The air entering through these apertures is heated by passing over the surfaces of a suitable baffle J² that is kept 105 heated by the heat from the producer so that when such heated air mingles with the hot gas from the producer the mixture spontaneously burns with great heat and the heat passes up through the combustion 110

chamber H' and out through a number of vents K opening from the top thereof and, if required leading to a common flue or stack for conveyance away to any desired point.

Means are placed within the combustion chamber, for the production of steam through the combustion of the gas therein. Such means may be of any suitable and convenient design providing for the complete utilization of the heating agency to heat the continuously flowing feed water, to convert such water into steam, and then to superheat the steam produced, and to provide for as great a quantity of water as is possible being thus treated.

Suitable means for the purpose are shown in the drawings. These comprise (1) a pipe coil M that is arranged to extend around the inside of the shell H from the bottom to the top thereof and the bottom end of which is connected to the water supply, (2) the jacket space G', previously described as surrounding the producer, and into the bottom of which the top end of the coil M is led, and (3) a series of water tubes N extending horizontally through the combustion chamber and connected with the top of the space G' and with a steam chamber O in the top of the combustion chamber. The feed water continuously passing up through the coil M is heated and passes into the jacket space G' in which it becomes subject to the heat radiating from the producer and in which it may be caused to circulate by the introduction of a medially disposed partition g extending from near the bottom to near the top of such space. The water will thus be practically converted into steam in its passage through this space and will pass out into the tubes N. These are shown as arranged in battery or grid form leading horizontally from the two vertical headers N', disposed diagonally opposite one another and connected at their bottoms with the top of the space G', through the pipes n to the vertical headers N² also disposed diagonally opposite one another and interposed between the headers N', and the tops of which lead up into the steam chamber O. The water or saturated steam passing from the jacket space G' will thus rise within the headers N' and pass from both sides of each through the tubes N and be superheated by the heat from the combustion of the gas as the liquid rises through these tubes, and then will pass to the headers N² and rise into the steam chamber O from whence it is led away for use as required through the steam pipe O'.

If desired, the passage of the heat through the combustion chamber may be checked, so as thereby to use it to greatest advantage, by the employment of a number of baffle plates P (Fig. 1) which will cause the heat

to take a zig zag course up through such chamber.

It will be seen that the feed water which enters the coil M flows once through a substantially continuous conduit, certain parts of said conduit being enlarged, these enlargements comprising the water jacket G and the headers N' and N². Each of the tubular grids by which the headers are connected also amounts to an enlargement, since the tubes N in each grid, if taken together, have more capacity than the tube M. There is open communication between the steam drum O and the introductory end of the feed coil M, so that it is necessary for the water to be fed into said coil with sufficient pressure to prevent the steam from causing back-flow. It is important that the flow of water be continuous, thereby to prevent the formation of stationary bubbles and the consequent overheating of the tubes at any point in the water system. The generator is extremely compact, since the water is heated only once, and does not circulate as in an ordinary circulating boiler.

After the water leaves the upper part of the water chamber G and passes through the series of tubes N, it receives a final increment of heat, or is superheated, and is in a highly heated and highly compressed condition when it reaches the vicinity of the expansion chamber O, where it expands into steam vapor. The water flows continuously from end to end of the system, but, owing to the heat that it receives at every stage, it takes the nature of compressed or liquid steam before it has opportunity to escape into expansion chamber O.

I claim:—

1. A steam generator comprising, in combination, a gas producer, an exterior shell, a feed water coil within said shell, a combustion chamber surrounded by said coil and surrounding said gas producer, a water jacket between said combustion chamber and said gas producer, said feed water coil communicating with said water jacket to deliver water thereto, a battery of pipes within said combustion chamber to receive fluid from said water jacket, and a steam chamber at the delivery end of the generator and in communication with said battery.

2. A steam generator comprising, in combination, a gas producer, an exterior shell, a feed water coil within said shell, a combustion chamber surrounded by said coil and surrounding said gas producer, a water jacket between said combustion chamber and said gas producer, said feed water coil communicating with said water jacket to deliver water thereto, a battery of pipes within said combustion chamber to receive fluid from said water jacket, and a steam chamber at the delivery end of the generator and

in communication with said battery; a distributing header being provided between said water jacket and said battery, and a collecting header between said battery and 5 said steam chamber.

3. A steam generator comprising, in combination, a gas producer, an exterior shell, a feed water coil within said shell, a combustion chamber surrounded by said coil 10 and surrounding said gas producer, a water jacket between said combustion chamber and said gas producer, said feed water coil communicating with said water jacket to deliver water thereto, a battery of pipes within 15 said combustion chamber to receive fluid from said water jacket, a steam chamber, a plurality of distributing headers being provided between said water jacket and said battery, and a plurality of collecting headers 20 between said battery and said steam chamber.

4. A steam generator comprising, in combination, a central gas producer, a water jacket surrounding the same, a combustion 25 chamber surrounding the water jacket and in communication with the gas producer, pipes in the combustion chamber and in communication with the delivery side of the water jacket, a steam chamber in communication with said pipes, and a water coil surrounding said combustion chamber and delivering water to said water jacket.

5. A steam generator comprising, in combination, a gas producer, a combustion 35 chamber in communication therewith, means for supplying air to the combustion chamber together with gas from the gas producer, a final heating coil in the combustion chamber, a water jacket between said coil and said gas producer and surrounding the latter, to deliver heated fluid to said coil, and a feed water coil around said combustion chamber.

6. A steam generator comprising, in combination, a gas producer, means for introducing air under pressure into the top of the gas producer, a combustion chamber surrounding the gas producer, ducts leading from the bottom of the gas producer to the 50 bottom of the combustion chamber, said gas producer having a grate and said ducts leading from a point above the grate, a water jacket surrounding said gas producer between the same and the combustion chamber, said combustion chamber having inlets 55 for air, heating plates over which the air flows into the combustion chamber, means within the combustion chamber for effecting the production of steam through the combustion of gas therein, said steam producing means being in communication with the delivery side of said water jacket, a feed water coil surrounding said combustion chamber and leading to the bottom of said water 60 jacket, said water jacket divided into pas- 65

sageways by annular partitions, and baffle plates in said combustion chamber, to cause the flames to pursue a zigzag course therethrough.

7. A steam generator comprising, in combination, a gas producer, means for introducing air under pressure into the gas producer, a combustion chamber surrounding the gas producer, ducts leading from the gas producer to the bottom of the combustion chamber, a water jacket surrounding said gas producer between the same and the combustion chamber having an air supply, means within the combustion chamber for the production of steam through the combustion of gas therein, and a feed water coil surrounding said combustion chamber and leading to said water jacket. 70 75 80

8. A steam generator comprising, in combination, a gas producer, a combustion chamber surrounding the gas producer, a water jacket surrounding said gas producer between the same and the combustion chamber, means within the combustion chamber for the production of steam through the combustion of gas therein, and a feed water coil included in said generator outside of 85 said producer but arranged to be heated in said generator and communicating with the intake side of said water jacket. 90 95

9. A steam generator comprising, in combination, a gas producer, a combustion chamber surrounding the gas producer, a water jacket surrounding the gas producer, 100 water tubes in said combustion chamber and in communication with the delivery part or side of said water jacket, a feed water coil within said generator but outside of said producer and communicating to said water jacket, and a steam chamber in communication with said tubes. 105

10. A steam generator comprising, in combination, a gas producer, a combustion chamber surrounding the gas producer, a water jacket surrounding the gas producer, water tubes in said combustion chamber and in communication with the delivery part or side of said water jacket, a feed water coil within said generator but outside of said gas producer and communicating to said water jacket, a steam chamber, and distributing and collecting headers for said tubes. 110 115

11. A steam generator comprising, in combination, a gas producer, a combustion chamber surrounding the gas producer, a water container arranged to be heated within said generator but without said gas producer, water tubes in said combustion chamber and in communication with the delivery part of said water container, a feed water coil within said generator but outside of said gas producer and in communication with said water container, a steam chamber, 120 125 130

- and distributing and collecting headers for said tubes.
12. A steam generator comprising, in combination, a gas producer, a combustion chamber comprising an inclosing wall, means exterior to the gas producer and within the wall for initially heating feed water, means between the gas producer and the combustion chamber for additionally heating the water received from said feed-water heating means, and means within the combustion chamber for further heating the fluid received from said additional heating means.
13. A steam generator comprising, in combination, a gas producer, a combustion chamber comprising an inclosing wall, means exterior to the gas producer and within the wall for initially heating feed water, means between the gas producer and the combustion chamber for additionally heating the water received from said feed-water heating means, means within the combustion chamber for further heating the

fluid received from said additional heating means, and a steam chamber at the delivery part of the generator.

14. A steam generator comprising a gas producer, a combustion chamber in communication therewith, a steaming system comprising pipes or tubes within said combustion chamber, a feed-water heating coil arranged without said gas producer, a receptacle for a body of water between said coil and said pipes or tubes, and also arranged without said gas producer, said feed-water heating coil delivering into said water receptacle, and the latter delivering to said pipes or tubes, said receptacle surrounding said gas producer and being surrounded by said combustion chamber.

In testimony whereof, I have signed this specification in the presence of two subscribing witnesses.
